UNITED STATES PATENT OFFICE.

DONALD H. REEVES, OF DAYTON, OHIO.

PNEUMATIC PUMP.

1,385,752.

Specification of Letters Patent. Patented July 26, 1921.

Application filed June 21, 1919. Serial No. 305,720.

To all whom it may concern:

Be it known that I, DONALD H. REEVES, a citizen of the United States, residing at Dayton, in the county of Montgomery and 5 State of Ohio, have invented certain new and useful Improvements in Pneumatic Pumps, of which the following is a specification.

This invention relates to a pneumatically 10 operated pump particularly designed for use on an airplane, to pump gasolene from the main tank to the gravity tank, or to the carbureters, or other desired point.

It is desirable, in aeronautic work, to use 15 compressed air for elevating gasolene to the gravity tank or to the carbureters; the pump of this invention utilizes compressed air as the operating means, and yet does not subject the main gasolene tank to air pressure. Obviously, if the main tank is at a 20 pressure greater than the atmospheric pressure, in order to cause proper flow of gasolene, the system becomes inoperative in case a bullet should puncture the tank, or should 25 it spring a leak.

The pump of my invention comprises two pressure chambers. In each chamber there is a bellows and the bellows are connected by a pipe, so that as one bellows expands, 30 the other contracts, the interiors of the two bellows being filled with a substantially incompressible fluid, such as glycerin. The use of the bellows avoids the use of reciprocating parts. The use of reciprocating 35 parts, in gasolene pumps has been found unsatisfactory on account of the difficulty in properly packing the piston and piston rod to prevent leakage of gasolene.

My invention further comprises means 40 for allowing the chambers to fill with gasolene, and means for alternately subjecting the two chambers to air pressure, so that either one chamber or the other is always delivering gasolene.

My invention further comprises means 45 for alternately venting each chamber, that is to say, means for allowing the air that fills the chamber after it has delivered its quota of gasolene, to escape to the top of the main gasolene tank, where it relieves 50 the suction there, and allows gasolene to fill the chamber that is being vented.

My invention further comprises means 55 for controlling the rate of flow of the liquid, such as glycerin, contained in the two bellows, from one bellows to the other,

an adjustment which controls the rate of pumping of the pump.

Other objects and advantages will appear as the description proceeds.

In the drawings, illustrating one embodiment of my invention, Figure 1 is a sectional view taken on a line passing through the valve chamber of the pump.

Fig. 2 is an inverted section of the pump, 65 taken on the line 2-2 of Fig. 1, and looking in a direction of the arrows.

Fig. 3 is a plan view of the pump.

Fig. 4, shows a section of the pump taken on the line 4-4 of Fig. 3.

Figs. 5, 6 and 7 are sections taken on the lines 5-5, 6-6 and 7-7, respectively, of Fig. 3.

Fig. 8, is a view showing the valve mechanism of Fig. 1 in another position.

Fig. 9 is a section on the line 9-9 of Fig. 4.

Referring now to Figs. 1 and 2, the two chambers of the pump are formed by a bottom wall 1, side walls 2, and a partition 3, which divides the space into two chambers, one of which I will call the valve chamber, indicated by V, and the other which I will call the auxiliary chamber, indicated by A.

A cover C, when placed in position as shown in Fig. 1 completes the two said chambers. The side walls 2 and cover C may be provided with appropriate lugs 4, suitably drilled for bolts 5 to secure the 90 cover in position.

A gasolene inlet pipe 6, preferably cast integrally with the cover C, is threaded as indicated at 7, for the attachment of a connection, not shown, leading to the bottom 95 of the main gasolene tank, not shown. This pipe 6 is provided with a downwardly extending branch 8, which merges into two branches 9, controlled by one way check valves 10, to deliver gasolene into the auxiliary chamber A. The pipe 6 also delivers gasolene to a precisely similar delivery pipe 8' provided with branches 9' and check valves 10' to deliver gasolene to the valve chamber V.

The cover C is also provided with a gasolene outflow pipe 11, which is threaded as at 12 for the attachment of a pipe leading to the gravity tank or the carbureters, not shown. Suitably mounted in the cover C 110 is a delivery pipe 13, which extends nearly to the bottom of the valve chamber V, and

which at its upper end opens into the out-flow pipe 11, this opening being controlled by the one-way upwardly opening check valve 14. A precisely similar pipe 13', provided with a check valve opens into the auxiliary chamber A and into pipe 11.

Cover C is further provided with a passage 15, which is in free communication with the auxiliary chamber A, at one end 10 and which is in communication with the valve chamber V under certain conditions to be described.

A recess 16 is cut in the bottom part of the cover C. In this recess is mounted the valve block 17. This block 17 is provided with a recess 18 for an air valve, which recess is narrowed at its upper and lower parts to form beveled valve seats. The upper part of the recess 18 is in communication with a hole 19 in the cover C which in turn is in communication with the passage 15. The valve block 17 is also provided with a recess 20, which is flaring at its upper and lower parts to form beveled seats. The upper part of the recess 20 is in communication with the passage 21, which in turn is in communication with the passage 15. The lower part of the recess 20 is open to the interior of the valve chamber V.

30 Mounted to move in the recess 18 is an air inlet valve 22, which when in its uppermost position as shown in Fig. 4 closes passage 18 to communication with the passage 15 and leaves it in communication with the valve chamber V. Valve 22 is provided with a guide 23 moving in the aperture 19 and is carried by a valve stem 24, provided with lugs 25 and 26. The lower end of the valve stem 24 is loosely mounted in the fixed 40 guide 27.

Mounted to move in the recess 20 is a vent valve 28, provided with valve faces 29 and 30, which when the valve is in its uppermost position as shown in Fig. 4 puts the passage 45 20 in communication with the passage 15 and closes the passage 20 to communication with the valve chamber V. Valve 28 is provided with a valve stem 24', lugs 25' and 26', and has its lower end mounted to move 50 loosely in a fixed guide 27'.

Referring now to Fig. 9, the valve block 17 is provided with a hole 31 which at one end communicates with the valve passage 18 and at its other end opens into the vertical 55 air inlet passage 32. This air inlet passage 32 communicates with an opening 33, which in turn registers with the air inlet pipe 34, to which is connected a supply of compressed air from any suitable source. This 60 air pipe 34 may be provided with a downwardly opening check valve 35.

The recess 20 for the vent valve is in communication with a passage 36, horizontally drilled as shown in Figs. 1 and 3. Passage 65 36 at its other end is in communication with

the vertical passage 37, which opens into the vent passage 38, in the cover C. A vent pipe 39 may be inserted in this opening 38 and at its other end, not shown, it opens into the top of the gasoline tank.

The guide 27' may be formed integrally with a substantially U-shaped element 40, which is secured to the under side of the cover C by the screw 41. The guide 27 may be formed integrally with an element 40' 75 precisely similar to the already described element 40. The two elements 40 and 40' are mounted in parallel relationship, spaced apart slightly so as to define a slot between them.

Pivottally mounted in this slot is a latch 42 on the pivot 43 carried by the two elements 40. The latch 42 is provided with upper and lower lugs 44 and 45, (see Figs. 1 and 8) which are adapted to operate with a yoke 46, that engages with the valve stems 24 and 24', and which is positioned between lugs 25 and 26 and 25' and 26', respectively, so that the yoke will move with both valve stems.

90 The latch 42 is provided with an extension 46' which at its lower end carries a transversely extending rod 47. Another rod 48 is carried by the two elements 40. A pair of springs 49, 49' have their lower ends engaging with the rod 47 and their upper ends engaging with the rod 48.

95 The latch 42 is provided with a rearwardly extending lug 42', the purpose of which will appear later.

Suitably attached to the under side of the cover C at their upper ends are two bellows, S and S', one positioned in the valve chamber V and the other in auxiliary chamber A. Each bellow is provided with a base plate 105 50, which in turn carries guiding elements 51 and 52, coöperating with a guide tube 53 carried by the cover C, all of which coöperate to effect smooth movement of the bellows. The cover C is provided with a pipe 54 preferably integral therewith which pipe through downwardly extending passages 55 and 56 is in communication with the interiors of the two bellows S and S'. Interpolated at a suitable point in the pipe 54 is a needle valve 110 55. The interiors of the two bellows, as well as the pipes 54, 55 and 56 are filled with some such liquid as glycerin, a cap 58 may be threaded on to the cover C over the needle valve to prevent leakage. The needle valve 115 may also carry a lock nut 59.

The bellows S has attached thereto the bent plate 60, the upwardly extending arm 61 of which is provided with a slot 62 in which slot engages the already described lug 120 42' of the latch 42.

125 The operation of the device will now be described. With the parts positioned as shown in Fig. 4, chamber V is presumed to be full of gasoline that has flowed in through 130

the inlets 9', by gravity and the chamber A is shown as venting. It will be noted from the position of the air valve 22 that the valve chamber V is being subjected to the air pressure from the compressed air pipe 34, it being led thereto through the passages 33, 32 and 31. This air pressure forces the gasoline contained in the chamber V upwardly through the delivery pipe 13 and into the outlet pipe 11. Valve 28 during this operation is closed with respect to the chamber V so that it is not in communication with the vent.

At the same time the air, in chamber A is escaping therefrom through the pipe 15 into the valve passage 20, passage 36, passage 37 and thence into the vent pipe 39, to the top of the gasoline tank. This relieves the air pressure in the chamber A and allows gasoline to flow into that chamber through the passages 9. While either chamber is subject to air pressure the check valves 10 or 10' will of course be closed to prevent entry of air into the pipes 8 or 8'.

25 The air pressure in the chamber V slowly compresses the bellows S and forces the glycerin contained therein through the pipe 54 into the other bellows S', thereby causing it to expand.

30 As the bellows S moves upwardly as described, it carries therewith the arm 61, (see Fig. 8), which gradually lifts the lug 42' of the latch 42, and so causes the latch 42 to turn about the pivot 43. During this operation it will be apparent that the rod 47 to which is attached the lower ends of the two springs as already described will move to the right so that the spring will tend to assume a position to the right of the pivot 43.

40 As soon as the spring passes this pivot 43 it will lift the lower end 46' of the latch 42 which in turn will depress the lug 44 of the latch 42 causing it to engage with the yoke 46 and force it downwardly, it, in turn, moving both the valve stems 24 and 24' downwardly to reverse the position of the two valves 22 and 28. This new position of the parts is shown in Fig. 8. In that position it will be understood that the air valve 22 is 45 in its lowermost position thereby letting in air pressure into the pipe 15 and subjecting the chamber A to air pressure.

At the same time the vent valve 28 is in its lowermost position and opens the chamber V to the vent.

Chamber V will now fill with gasoline and the air contained therein will escape through the vent. Chamber A, being subjected to air pressure will force gasoline out through the delivery pipe 13' into the outlet pipe 11, the check valve 14 lifting to allow this outflow. The bellows S' is now expanded and the bellows S contracted. The air pressure now on the chamber A forces the bellows S' 60 to contract again which causes a flow of

glycerin back into the bellows S and an expansion of the same. As bellows S expands the upper edge of the slot 62 will bear against the lug 42' and carry it downwardly to cause the projection 46 to move to the left, 70 as shown in Fig. 1 until the springs 49 pass by the pivot 43, whereupon the springs will cause the latch 42 to move back into the position shown in Fig. 1 to reverse the positions of the valves 22 and 28 and start the 75 cycle of operations just described over again. It will be apparent that the rate of operation of the pump is dependent upon the rate of the contraction and expansion of the bellows, and the latter in turn is dependent 80 upon the rate of flow of the glycerin from one bellows to the other. By providing the needle valve 55 to control the flow of glycerin it will be apparent that the rate of operation of the bellows, and consequently the 85 speed of the pump, can be regulated. In place of glycerin any suitable liquid could of course be used.

While I have illustrated a particular embodiment of my invention it should be understood that it could be carried out in other ways, as defined in the following claims.

I claim as my invention:—

1. In a pneumatic pump, two pump chambers, a compressed air supply, a vent for 95 said chambers, a compressed air inlet valve controlling both chambers, a vent valve common to both chambers, and intercommunicating bellows in said chambers operable by the compressed air and adapted to actuate both of said valves, the movement of said valves by the bellows being independent of the pumping action.

2. In a pneumatic pump, two pump chambers, a compressed air supply, air inlet valve 105 arranged to admit air under pressure to said chambers, a vent valve common to both chambers, and bellows in said chambers having operative connection with said valves to simultaneously shift them to admit compressed air to one chamber and at the same time vent the other chamber, the movement of said valves by the bellows being independent of the pumping action.

3. In a pneumatic pump, two pump chambers, a compressed air supply, air inlet valve arranged to admit air under pressure to said chambers, a vent valve common to both chambers, bellows in said chambers having operative connection with said valves to 115 simultaneously shift them to admit compressed air to one chamber and at the same time vent the other chamber, the movement of said valves by the bellows being independent of the pumping action, and a fluid pressure transmission passage placing said bellows in communication with each other.

4. In a pneumatic pump, two pump chambers, a compressed air supply, an air inlet valve arranged to admit air under pressure 120

to said chambers, a vent valve common to both chambers, bellows in said chambers having operative connection with said valves to simultaneously shift them to admit compressed air to one chamber and at the same time vent the other chamber, the movement of said valves by the bellows being independent of the pumping action, a fluid pressure transmission passage placing said bellows in communication with each other, and means for varying the capacity of said passage to regulate the speed of flow of the fluid therethrough.

5. In a pneumatic pump, two pump chambers, a compressed air supply, valve means to admit compressed air to one chamber and simultaneously vent the other chamber, and actuating means for said valve means em-

bodying bellows in said chambers having connection with said valve means, the movement of said valve means by the bellows being independent of the pumping action, said bellows being in open pressure communication with each other. 20

6. In a pneumatic pump, two pump chambers, a compressed air supply, valve means controlling the admission of compressed air to and the venting of said chambers, and interdependent fluid pressure connected bellows in said chambers having operative connection with said valve means, the movement of said valve means by the bellows being independent of the pumping action. 25

In testimony whereof I affix my signature.

DONALD H. REEVES.
